Inventor,
G.R. Watson, by
G.C. Kennedy,
Attorney.

UNITED STATES PATENT OFFICE.

GEORGE R. WATSON, OF WATERLOO, IOWA, ASSIGNOR TO ARMSTRONG MANUFACTURING COMPANY, OF WATERLOO, IOWA, A CORPORATION OF DELAWARE.

WELDLESS DRILL JAR.

1,405,468.

Specification of Letters Patent. Patented Feb. 7, 1922.

Application filed September 24, 1920. Serial No. 412,576.

To all whom it may concern:

Be it known that I, GEORGE R. WATSON, a citizen of the United States of America, and a resident of Waterloo, Black Hawk County, 5 Iowa, have invented certain new and useful Improvements in Weldless Drill Jars, of which the following is a specification.

This invention relates to improvements in weldless drill-jars, and the object of my 10 improvement is to supply jars of drilling tools which are so constructed as to be free from welds to thereby strengthen them, this construction being effected by a method suited to the purpose.

15 I have accomplished this object by the method and construction which are hereinafter described and claimed, and which are illustrated in the accompanying drawings, in which Fig. 1 is an elevation of the 20 slidably interlocked members of my improved jar; Fig. 2 is a like elevation of the device with parts of one member or rein in medial longitudinal section; Fig. 3 is an elevation of the parts shown in said Fig. 1, 25 at an angle of ninety degrees therefrom; Fig. 4 is a medial longitudinal section taken along the plane of meeting of the abutting flat faces of the members of the device; Figs. 5 and 6 are like perspective views of the 30 upper member, the locking feather being shown respectively in incomplete and in finished condition, and Fig. 7 is a cross-section of said interlocked members taken on the broken line 7—7 of said Fig. 1.

35 Similar numerals of reference denote corresponding parts throughout the several views.

Drill-jars for well-drilling tools are usually interlinked closed looped members or 40 reins interlocked against all but limited longitudinal sliding movements relative to each other. The parts of each pair of reins which are adjacent the head of the member are welded to the head, commonly by tongue 45 and groove joint. This junction of the reins with the head is termed the "anvil" because it has to sustain the jarring impacts of the adjacent or hammer end of the other sliding member at times when the 50 device is being actuated by to and fro sudden movements in the direction of its length in order to dislodge tools connected to the device which have become lodged in a drill-hole. This welded junction part thus is 55 subjected to severe concussions which tend

to crystallize its structure and also, to fracture it at the welded surfaces, especially, if there is some imperfection in the welding. Such a fracture often results in the loss of the drilling tools, and even in necessary abandonment of the drill-hole because of an impossibility of removing the tool by grappling or other means.

I have, therefore, in this invention adopted such a construction of and method of 65 interlocking the linked members as will obviate any necessity for welds in either member.

The drill-jar device illustrated contains two members 1 and 10 which are alike in 70 form, except that the upper member 1 has a threaded frustal stud 2 for connection with a coupling member, not shown, on a tool-carrying cable, while the head of the other member has a counterpart interiorly 75 threaded socket 11 for connection with a similar stud on a suspended tool. Each member has its head portion squared at 3 to receive a wrench. Each of said members has from a shoulder 4 a part 5 extending thence, the part 5 being semi-cylindrical with a flat face in a longitudinal medial plane intersecting the axis of the member, so that when the two members 1 and 10 are 80 reversed relatively to each other both longitudinally and transversely, the flat surfaces of their parts 5 may have longitudinal sliding contact. The part 5 has a medial longitudinal slot 6 starting from the head 1 at or about the shoulder 4, and extending 85 about half way along its length. This slot is relatively narrow from the flat face of the member outwardly, but is gradually widened outwardly as shown in Fig. 7, starting from a limit somewhat more than 90 one-half of its depth. On the flat face of each part 5, extending longitudinally and medially from its extremity 12 which is slopingly reduced from each side, is a laterally projecting feather or key 8 whose width 95 is but slightly less than the narrower width of the slot 6 in the other member 10 in which it is longitudinally slid able. Initially, the feather 8 is of the tabular form shown in 100 Fig. 5, so that when it is mounted in the slot 6 of the opposite member it will project therebeyond. When said incomplete members are thus assembled, the outer parts of the feathers 8 are appropriately treated to upset them and widen them at 9, so that the 110

widened terminals 9, as shown in Fig. 7, slidably fit the outer wider opening 7 of the slot 6, with the outer face of the feather 9 flush and of the same curvature with the outer cylindrical surface of the part 5. This feather 8, and its upset terminal 9, interlocks said members 1 and 10 for relative longitudinal sliding movements only.

This method of construction of the members obviates welding and thus the heads 1, at their junctions with the reins 5 at the shoulders 4, are freed from any structural weakness, such as would be due to welding at this location.

Having described my invention, what I claim as new, and desire to secure by Letters Patent, is:

1. A weldless drill-jar, comprising two members interlocked for relative longitudinal movements, each member being longitudinally slotted, and each member having a lateral feather mounted in the longitudinal slot of the other and terminally upset to lock it to the other member.
2. A weldless drill-jar, comprising two members, each member being provided with a longitudinal slot having two lateral

widths, and each member having a lateral longitudinal feather whose body slidably fits the narrower part of the slot in the other member, the outer edge part of each feather being upset to slidably fit the wider part of the slot in the other member.

3. The method of making drill-jars, which consists in interlocking two partially formed members, each having a longitudinal slot and a lateral projection fitting the slot in the other member, with each projection projecting beyond said slot, upsetting the projecting part of each projection to render it terminally wider than the width of the slot.

4. The method of making drill-jars, which consists in interlocking two partially formed members, each having a longitudinal slot of two widths and a lateral projection fitting the narrower and adjacent part of the slot in the other member to project through the slot and beyond it, upsetting the projecting part of each projection terminally to slidably fit the wider part of the slot.

Signed at Waterloo, Iowa, this 27th day of August, 1920.

GEORGE R. WATSON,
